UNITED STATES PATENT OFFICE.

EDWARD FERGUSON CHANCE, OF WEST SMETHWICK, NEAR BIRMINGHAM, ENGLAND, ASSIGNOR TO CHANCE BROTHERS & COMPANY, LIMITED, OF SAME PLACE.

DESIGN FOR THE ORNAMENTATION OF GLASS.

SPECIFICATION forming part of Design No. 20,044, dated July 22, 1890.

Application filed June 25, 1890. Serial No. 366,724. Term of patent 14 years.

To all whom it may concern:

Be it known that I, EDWARD FERGUSON CHANCE, managing director of CHANCE BROTHERS & COMPANY, (Limited,) glass-manufacturers, of West Smethwick, near Birmingham, England, a subject of the Queen of Great Britain, have invented and produced a new and original Design for the Ornamentation of Rolled Plate Glass, of which the following is a specification, reference being had to the accompanying drawing, forming part thereof.

This design is shown in front view and sectional view in the drawing, and is composed of a series of irregularly-shaped ornamental figures, such as *a b c*, marked on the drawing, the said figures being grouped substantially as shown. Each of these ornamental figures is subdivided by a series of parallel

depressions having inclined or beveled sides. These subdivisions, as they approach the center of the figure, are made preferably to approach each other, the vertical heights of the summits of the subdivisions diminishing as the said divisions approach the center of the figure, as shown by the sectional view.

What I claim is--

A design for the ornamentation of rolled plate glass, consisting of grouped irregularly-shaped ornamental figures subdivided, as set forth.

In testimony whereof I have affixed my signature in presence of two witnesses.

EDWARD FERGUSON CHANCE. [L. S.]
